CLAIM

The ornamental design for a bag, as shown and described.

DESCRIPTION

FIG. 1 is a perspective view of a bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the bag where the bag is in a configuration of use.

The dark, thick broken lines on claimed surfaces in the drawings depict stitching of the bag and form no part of the claimed design. The chain shown with light, thin broken lines in FIG. 9 depicts environment of the bag and forms not part of the claimed design. All other broken lines in the drawings depict portions of the article and form no part of the claimed design.

1 Claim, 9 Drawing Sheets(56)
